UNITED STATES PATENT OFFICE.

MICHAEL SHUTER AND ABRAHAM DAVIS, OF NEW YORK, N. Y.

TIP FOR INSOLES.

SPECIFICATION forming part of Letters Patent No. 242,382, dated May 31, 1881.

Application filed May 2, 1881. (Model.)

To all whom it may concern:

Be it known that we, MICHAEL SHUTER and ABRAHAM DAVIS, both citizens of the United States, residing at New York, in the county 5 and State of New York, have invented new and useful Improvements in Tips for the Insoles of Boots and Shoes, of which the following is a specification.

This invention relates to tips for the insoles 10 of boots and shoes, and is an improved manufacture, consisting of a tip formed of muslin or the like, stiffened with shellac or other similar material, and pressed into shape.

Prior to our invention a tip for the insole of 15 boots and shoes has been made of leather, and usually in one piece with the insole, the tip being beveled to a fine edge at the top. This mode of producing the tip, however, is objectionable, because requiring skill and consider- 20 able labor.

By our invention we are enabled to produce a tip which is sufficiently thin to require no beveling, and at the same time is sufficiently rigid for all purposes.

25 This invention is illustrated in the accompanying drawings, in which Figure 1 represents a vertical cross-section of the tip. Fig. 2 is a plan view thereof. Fig. 3 shows it attached to the insole. Figs. 4 and 5 illustrate 30 the process of making the tip, Fig. 5 being a section on the line $x-x$, Fig. 4.

Similar letters indicate corresponding parts.

In carrying out our invention we take a piece of muslin or other textile material and

coat the same with shellac to render the same 35 stiff or rigid. Then, having allowed the shellac to dry, we place the material between heated dies, the form of which is such that the material is thereby pressed into the general shape of a series of tips, as at A⁰, Figs. 4 and 5. We 40 then subject the pressed or molded material to the action of cutters, whereby it is severed, as along the dotted lines shown in Fig. 4, and the portions A⁰ are separated from each other, each constituting a tip, A, Figs. 1, 2, and 3, 45 suitable for the insole B of a boot or shoe.

It will be seen that the tip formed in this manner requires no beveling, the material used being sufficiently thin, while it possesses similar or superior rigidity to a leather tip, so that 50 while the cost of its manufacture is comparatively low it is an effective substitute for the leather article.

What we claim as new, and desire to secure 55 by Letters Patent, is—

As an improved article of manufacture, a tip for the insole of boots and shoes formed of textile material stiffened with shellac and pressed into shape, substantially as and for the purpose described.

In testimony whereof we have hereunto set our hands and seals in the presence of two subscribing witnesses.

MICHAEL SHUTER. [L. S.]
ABRAHAM DAVIS. [L. S.]
